PORTABLE STEAM GENERATOR

Filed April 25, 1947

UNITED STATES PATENT OFFICE

2,572,317

PORTABLE STEAM GENERATOR

Wilfred G. Chausse, Detroit, Mich.

Application April 25, 1947, Serial No. 743,850

2 Claims. (Cl. 122—4)

1

This invention relates to steam generators and in particular to portable steam generators.

One object of this invention is to provide a light-weight and compact steam generator which may be transported from place to place with ease yet which may be quickly set up at its place of intended use and steam generated in a very short period of time.

Another object is to provide a portable steam generator which is specially adapted for use in winter, which is provided with runners by which it may be transported over snow or ice and which is also provided with retractable wheels for use on stretches of bare ground.

Another object is to provide a portable steam generator wherein the generator is instantly movable from a horizontal transporting position to a vertical steam generating position and which is capable of producing sufficient steam in a very short period of time for thawing out frozen equipment, such as fire hydrants, and rendering them usable in a shorter time than has heretofore been possible or practical.

Another object is to provide an oil-fired portable steam generator as set forth in the preceding objects wherein the entire generator is self-contained in a single unit, including tanks of water and oil, the necessary pumps, oil burner, and steam generating coils.

In the drawings:

Figure 1 is a front elevation, partly in section, of a portable steam generator according to a preferred form of the invention, with the ground wheels in their retracted positions;

Figure 2 is a right-hand side elevation of the portable steam generator shown in Figure 1;

Figure 3 is a horizontal cross-section taken along the line 3—3 in Figure 1; and

Figure 4 is an enlarged approximately horizontal cross-section taken along the line 4—4 in Figure 2 and showing the locking device for the retractable ground wheels.

Referring to the drawings in detail, Figures 1 and 2 show a portable steam generator, generally designated 10, according to a preferred form of the invention as including a tubular housing 11 with an annular conical top portion 12 terminating in a tubular flue 13. The housing 11 is provided with a cutaway opening 14 at the front thereof for rendering the interior accessible and this may be closed, if desired, by a suitable door (not shown). In order to transport the steam generator 10, the housing 11 has welded thereto a plurality of outer and inner struts or braces 15 and 16 respectively (Figure 3) converging toward one another and secured at their points of convergence 17 to a pair of runners 18.

Secured as by welding to the housing 11 is a tubular bearing member 19 (Figure 3) which is braced at its opposite ends by struts 20 welded at their upper or forward ends to the bearing member 19 and at their lower or rearward ends to the runners 18. Mounted in the bearing bore 21 of the bearing member 19 is the central por-

2

tion 22 of an axle 23 having crank arms 24 terminating in aligned end portions 25. Rotatably mounted upon the end portions 25 and secured thereto by the nuts 26 threaded thereon are the hubs 27 of ground wheels 28 equipped with the usual rubber tires 29.

Due to the offset axes of the end portions 25 from the central portion 22 of the axle 23, the ground wheels 28 may be swung from the solid line position to the dotted line position shown in Figure 2 when it is necessary to move the steam generator over stretches of bare ground. In order to lock the ground wheels 28 in their lowest positions (Figures 2, 3 and 4), the bearing member 19 is provided with an ear 30 welded thereto in spaced parallel relationship with one of the struts 20, these having aligned holes 31 and 32 respectively (Figure 4) for slidably receiving a reciprocable locking bolt 33 having a bent handle portion 34. The locking bolt 33 is urged to the right in Figure 4 into its locking position by means of a coil spring 35 having one end abutting the ear 30 and the other abutting the washer or annular shoulder 36 secured to the locking bolt 33. Thus the bolt 33 may be retracted with one hand and the ground wheels 28 moved into their supporting position with the other hand, the bolt 33 being released when the supporting position is reached, as shown by the dotted or chain lines in Figure 2. Conversely, when the bolt is retracted, the crank arms 24 are permitted to swing upward into their retracted positions shown by the solid lines in Figures 1 and 2, thereby enabling the runners 18 to be used for transporting the vehicle over ice or snow-covered ground.

Mounted in the lower part of the housing 11 is an oil tank 37 having a tubular filling connection 38 closed by a cap 39. The oil tank 37 is also provided with an air pump 40 having a reciprocable plunger 41 which is manually operable to fill the oil tank 37 with compressed air in order to force the oil therein upward through the oil supply pipe 42, through the stop valve 43, through the spiral preheating coil 44 to the burner nozzle 45 containing the spray orifice 46.

Mounted above the burner nozzle 45 is a tubular flame guide 47 secured to an angle bracket 48, the lower end of which is secured as by welding to the top of a water tank 49 which is mounted in the housing 11 immediately above the oil tank 37. The water tank 49 is similarly provided with an air pump 50 having a manually operable plunger 51 for supplying compressed air to the water tank 49 for the purpose of forcing water therefrom upward into the water supply pipe 52. The water tank 49 is also provided with a filling connection 53 closed by a cap 54.

The water under the pressure of the compressed air in the water tank 49 is forced upward through the water supply pipe 52 and stop valve 55 into and through the spiral steam generator coils 56 located immediately above the burner nozzle 45 in the housing 11. The casing 11 is provided with a partition or baffle 57 with a central

3

aperture 58 above the steam generator coils 56 and beneath the flue 13. The outlet pipe 59 of the steam generating coil 56 passes upward through holes 60 and 61 in the baffle 57 and top 12 and terminates in a short length of pipe 62 threaded to receive the hose connection 63 of a steam hose 64. The latter is equipped with any suitable nozzle (not shown) by which the steam may be applied to the equipment to be thawed out.

From Figures 1 and 2 it will be evident that the placing of the fuel tank 37 and water tank 49 superimposed upon one another at the bottom of the steam generator maintains the center of gravity of the generator in the lowest possible position. This arises by reason of the fact that the liquid fuel and water are very heavy. By placing them at the lowest possible location in the steam generator, the danger of tipping over the generator is minimized. Furthermore, it will also be evident from Figures 2 and 3 that the sled runner structure 15, 16, 18, 20 adds to the strength and rigidity of the steam generator by forming a bracing framework as well as a rest and sled when the steam generator is in a horizontal position. Moreover, when the steam generator is in a vertical position, the bottom ends of the runners 18, being substantially on the same level as the bottom 65 of the steam generator but spaced laterally away from it, thereby add to the stability of the steam generator against overturning, by increasing the effective size of the base.

Operation

In the operation of the invention, the fuel oil and water tanks 37 and 49 are filled with fuel oil and water respectively. Assuming that the ground is snow or ice-covered, the ground wheels 28 are retracted in the previously-described manner and the steam generator 10 is tilted into a horizontal position, wherein the runners 18 rest upon the ice or snow-covered ground. The device is then towed to its location of use where, for example, it is desired to thaw out equipment such as a fire hydrant. The steam generator is then tilted up on end with its housing 11 vertical and its bottom portion 65 resting upon the ground. The stop valves 43 and 55 are then opened and the air pumps 40 and 50 operated by reciprocating their plungers 41 and 51 in order to compress the air in the upper portions of the oil and water tanks 37 and 49 respectively. The oil forced up through the oil supply pipe 42 emerges from the orifice 46 of the nozzle 45 and is ignited in any conventional way such as by applying a lighted match thereto. The flame passing upward through the tubular flame guide 47 heats the pre-heating coil 44 and enhances the vaporization of the fuel oil emerging from the nozzle 45. This results in an intensely hot flame which, passing through the steam generating coil 56 and outward through the aperture 58 and flue 13, changes the water in the coil 56 to steam. The steam thus generated flows upward through the pipes 59 and 62 and outward through the steam hose 64 to the nozzle, which has been directed at or into the equipment to be thawed out.

By the use of this steam generator, it is now possible to thaw out a frozen fire hydrant in a very short period of time after the arrival of the steam generator. Thus, the hazard of being without water at the time of fires in extremely cold weather is eliminated where the cause of the water shortage is a frozen fire hydrant.

When it is necessary to tow the steam genera-

4

tor over bare ground, the ground wheels 28 are swung downward around the central portion 22 of the axis 23 as an axis, while the bolt 33 is retracted manually, one of the crank arms 24 being locked in its advance position by releasing the bolt 33 at the proper time. The ground wheels now occupy the dotted or chain line position shown in Figure 2, raising the rearward ends of the runners 18 off the ground. The steam generator 10 may then be towed as a wheeled trailer over bare ground instead of being towed as a sled.

What I claim is:

1. A portable steam generating apparatus comprising an elongated housing structure, a steam generator in said housing structure, said housing structure including, a base having an end rest connected to the end of said housing structure for supporting said housing structure in a vertical-steam-generating position, a sled runner structure connected to the side of said housing structure and extending therewith for supporting said housing structure in a horizontal travelling position, said runner structure including runner supports secured to and extending outwardly from said housing structure, and runners mounted on said runner supports in spaced relationship with said housing structure, an axle swingably mounted on said housing structure for motion toward and away from said runner structure, and ground wheels mounted on said axle.

2. A portable steam generating apparatus comprising an elongated housing structure, a steam generator in said housing structure, said housing structure including, a base connected to the end of said housing structure for supporting said housing structure in a vertical steam-generating position, a sled runner structure connected to the side of said housing structure and extending therewith for supporting said housing structure in a horizontal travelling position, said runner structure including runner supports secured to and extending outwardly from said housing structure, and runners mounted on said runner supports in spaced relationship with said housing structure, an axle swingably mounted on said housing structure for motion toward and away from said runner structure, ground wheels mounted on said axle, and a latch connected to said housing structure and engageable with said axle for locking said axle in its lowered position with said wheels disposed below said runner structure.

WILFRED G. CHAUSSE.
